UNITED STATES PATENT OFFICE.

GEORG GIESECKE AND WALTER GIESECKE, OF LEIPSIC, GERMANY.

DRIVING APPARATUS FOR PRINTING-MACHINES.

SPECIFICATION forming part of Letters Patent No. 668,350, dated February 19, 1901.

Application filed March 23, 1900. Serial No. 9,911. (No model.)

To all whom it may concern:

Be it known that we, GEORG GIESECKE and WALTER GIESECKE, subjects of the Emperor of Germany, and residents of Leipsic, Germany, have invented certain new and useful Improvements in Printing - Machines, (for which we have obtained patents in Germany, dated September 10, 1899, Nos. 115,550 and 115,551,) of which the following is a specification.

In the usual construction of two-revolution cylinder printing-machines the printing-cylinder receives its motion from the main driving-shaft by means of an intermediate gear-wheel which turns upon a supporting-shaft rigidly attached to the frame of the machine. In machines of this type the cylinder is usually raised when not in the act of printing and is lowered to make the impression—that is to say, the cylinder rises and falls once for each impression made. Owing to this movement the gear-wheel on the end of the cylinder-shaft does not perfectly mesh with the intermediate gear-wheel when the cylinder is raised, and the result is that considerable lost motion and backlash occur during a part of the action of the cylinder. Up to this time little significance has been attached to this defect in this class of machines, probably because it was supposed that it was quite sufficient if the cylinder gear-teeth during actual printing were in normal contact—*i. e.*, that the teeth touched one another in the pitch-lines; but the cylinder, as well as the mechanism connected with it, has also, when the impression has taken place and the cylinder is in the elevated position, various functions to perform which are of importance for the work of the machine—as, for example, the opening and closing of the grippers, the raising and lowering of the laying-on gages, the lifting and lowering of the sheet-holder, the action of the fliers, &c. All these functions are dependent upon the cylinder, and therefore its motion influences them all. We have found that these functions in the two-revolution machines are not executed with the regularity and smoothness which is absolutely indispensable to a faultless impression, and the cause of the disturbances in the action of the mechanism dependent upon the cylinder we have discovered to be the circum-

stance that the cylinder-wheel during a part of its revolution does not perfectly fit into the cogs of the driving-wheel. For these reasons we have devised and applied an improvement to the two-revolution machines which secures complete equality of interpenetration between the teeth of the wheels whether the cylinder be raised or lowered.

In carrying out our invention we mount the intermediate gear-wheel upon a movable shaft and provide automatic means for moving this shaft and gear-wheel relatively to the main driving-gear wheel and the cylinder gear-wheel in a manner to secure the smooth and uniform action of the machine at all times during the different positions of the cylinder.

In the accompanying drawings, Figure 1 is a side elevation of that portion of a printing-machine to which our invention relates and showing one form of our invention applied thereto. Fig. 2 is a vertical section on the line A B, Fig. 1. Fig. 3 is a side elevation of a modified form of our invention. Fig. 4 is an elevation and partial section on the line C D, Fig. 3. Fig. 5 is an elevation of another modification of our invention. Fig. 6 is an elevation and partial section on the line E F, Fig. 5.

Like numerals of reference designate like parts wherever they occur in the different views.

Referring to Figs. 1 and 2, the numeral 1 designates the main driving-gear, 2 is the intermediate gear, and 3 the cylinder gear-wheel. The gear-wheel 1 is rigidly fixed to the main driving-shaft 4. The intermediate gear-wheel 2 is mounted upon a stub-shaft 5, and the gear-wheel 3 is keyed to the cylinder-shaft. Toggle-levers 7 are journaled upon the main shaft 4 at one end 7^a, and their opposite ends 7^b are loosely mounted upon the stub-shaft 5. A toggle-arm 8 has a bearing 8^a, loosely journaled upon the stub-shaft 5, and at its opposite or upper end a bearing 8^b is mounted to turn on the cylinder-shaft 6.

As shown in Figs. 3 and 4, a double elbow-lever 7^b is fulcrumed upon the main shaft 4, and the two members 7 of this lever are journaled upon the stub-shaft 5, while the members 8 of said lever have journaled between them upon a pin 10 an eccentric-arm 11. A cam or eccentric 13 on the end of a

shaft 12 has a bearing in the lower end of the arm 11, and a cam 16 on said shaft 12 has a bearing in a hanger connected to the lower end of a connecting-rod 17, the upper end of which is journaled upon the cylinder-shaft 6. The operation of this construction is such that as the cylinder is raised by the cam 16 and the connecting-rod 17 the intermediate gear-wheel is moved by the cam 13 to a position under the gear-wheel 3. It will be understood that these relative movements are properly timed, so that the intermediate gear-wheel 2 moves in and out as the cylinder-gear 3 rises and lowers and the teeth of the gear-wheels 2 and 3 are always properly in mesh, preventing lost motion and backlash.

As shown in Figs. 5 and 6, an adjustable cam 14 surrounds the end of shaft 12 and has a bearing in the lower end of an arm 18, fulcrumed on the main shaft 4. The cam 14 may be adjusted to regulate the throw of fork 7, which carries the intermediate gear-wheel 2. The remaining parts shown in Figs. 5 and 6 are substantially the same as shown in Figs. 3 and 4 and operate in the same manner.

It will be obvious from the foregoing that as the cylinder is raised and lowered the intermediate gear-wheel 2 is always in close mesh with the wheels 1 and 3, thus insuring

a smooth and regular movement without 30 backlash, noise, or lost motion.

Having thus fully described our invention, what we claim is—

1. In a printing-machine, a main driving-shaft, a gear-wheel thereon, an impression-cylinder having a gear-wheel fixed to its shaft, an intermediate gear-wheel in mesh with the gear on the main shaft and the gear on the cylinder-shaft, and means for moving the intermediate gear-wheel in and out as the cylinder raises and lowers, to insure the proper mesh of the gear-teeth, substantially as described.

2. In a printing-machine, a main gear-wheel, a gear-wheel on the impression-cylinder, an intermediate gear between said two gear-wheels, toggle-arms for moving said intermediate gear-wheel as the cylinder is raised and lowered, and means for raising and lowering the cylinder.

In testimony that we claim the foregoing as our invention we affix our signatures in presence of two witnesses.

GEORG GIESECKE.
WALTER GIESECKE.
